SUBMARINE VESSEL

Thomas J. Athey, 1545 Royal Blvd., Glendale, Calif.

Filed Aug. 6, 1962, Ser. No. 71,180

Term of patent 14 years

(Cl. D71—1)

FIG. 1 is a side elevational view of a submarine vessel showing my new design,

FIG. 2 is a top plan view, and

FIGS. 3 and 4 are, respectively, elevational views of the stem and stern of the vessel, and

FIG. 5 is a sectional view on the line 5—5 of FIG. 2.

The side not shown is a mirror image of the side shown in FIG. 1.

I claim:

The ornamental design for a submarine vessel, substantially as shown and described.
